2

According to another feature characterising this invention the afore-mentioned locking action is obtained either by using the electromagnet of the drive control means or with the assistance of a power member other than said drive control means.

Other features of this invention will appear more clearly as the following description proceeds with reference to the accompanying drawings illustrating diagrammatically by way of example a few typical forms of embodiment of this invention. In the drawings:

FIGURE 1 illustrates diagrammatically the more of operation of a conventional starter motor drive;

FIGURE 2 illustrates the core of the control electromagnet and the fork head after the energizing circuit of the starter motor has been switched off;

FIGURE 3 illustrates the relative position of the core strap and of the fork head at the beginning of an engine starting operation;

FIGURE 4 shows a first form of embodiment of the locking device according to this invention;

FIGURE 5 illustrates another form of embodiment of this device which provides a friction action;

FIGURE 6 shows a different form of embodiment providing a self-locking action;

FIGURE 7 shows another form of embodiment of the locking means;

FIGURE 8 shows another form of the embodiment using a bell-crank locking means.

FIGURE 9 shows a further form of embodiment providing a self-locking action, and

FIGURE 10 is a wiring diagram of the device illustrated in FIGURE 9.

In the conventional starter motor drive arrangement as illustrated diagrammatically in FIGURE 1 an electromagnet 1 comprises one or a pair of windings 2, 3 adapted to attract a soft-iron core 4. The wiring diagram of the windings is associated with the wiring diagram of the starter motor; thus, the winding 3 is connected to the circuit of the series-wound motor 5 of the starter motor; a storage battery 6 provides energizing current for the pair of windings 3, 3 via a starter switch 7 and for the motor directly through the main switch 8 responsive to said core 4. When switch 7 is closed, both windings 2 and 3 are energized and thus attract the core 11, whereby the latter, by means of the cross-pin 9 carried by its end strap 10, carries along the head of the fork 4 by causing the latter to pivot about its fulcrum pin 12. The fork 11 thus positively controls in turn the movement of the drive (not shown) towards the fly-wheel ring by means of shoes, clamps, studs or like member 13. Then the starter motor is energized under a reduced voltage until the core 4 closes switch 8 (as shown in FIGURE 1), thus short-circuiting coil 3 and causing the motor starter 5 to operate under maximum power conditions. When the engine begins to fire, switch 7 is re-opened and the pair of windings 2 and 3 are de-energized.

The reaction produced by the helical splines of the armature shaft on the starter drive keep the latter in meshing engagement with the fly-wheel ring if the engine does not start; now if some "cut-out" play were not provided, the fork action would prevent any opening of the main switch 8.

This cut-out play "J," which may be obtained in various ways, is illustrated diagrammatically in FIGURE 2 in the form of a lost motion of pin 9 in the strap of plunger-core 4 in relation to the two arms 14 and 15 of the U-shaped head of fork 11. The current is cut out in the main switch 8 when the cross pin 9 is caused to engage the front arm 14 by the return spring 16 (also visible in FIGURE 4), the drive being in its operative position in this case. As the return spring keeps urging the core 4 backward during

ABSTRACT OF THE DISCLOSURE

A positive-control electric starter for an internal combustion engine. Means are provided to ensure that the structure of the starter is positively locked in position when the starter is inoperative. The drive mechanism of the engine is prevented from reaching the toothed fly-wheel of the engine by providing structure intermediate the drive mechanism and the electromagnet associated with the starter for perfecting the locking operation.

This invention relates to electric starter motors of the positive control type, notably for internal combustion engines.

It is known to use electric starter motors wherein a drive adapted to be connected to the engine is disengaged therefrom automatically, usually by spring means, when the engine is running, this drive consisting as a rule of a pinion, a free-wheel device and members associated therewith which are adapted to slide in straight or helical splines formed in the starter motor shaft. When it is desired to start the engine, positive control means urge the drive towards the toothed ring of the engine fly-wheel until the drive pinion is in meshing engagement therewith.

This positive control action was formerly actuated by using a pull knob but nowadays the use of a plunger-core electromagnet or solenoid acting upon a drive fork has become widespread.

In either case the return spring restores the drive to its initial position when the engine is running and the drive is disconnected.

Now due to the developments of modern engines, notably their lighter weight and the increment in their rotational speed, more and more considerable vibration is produced and attended by very small relative movements of the various component elements; now these small displacements of the movable parts, notably of the drive on the splined armature shaft, are a source of considerable wear and tear, accompanied by a degradation of the lubricant (grease), and, moreover, by a tendency of the pinion to crawl towards the fly-wheel ring. As a result, the drive tends to compress its return spring balancing the stray driving forces caused by said vibration.

In certain types of engines and under certain conditions it may happen that this state of balance is not reached when the drive pinion engages the fly-wheel ring; as a consequence, the pinion is "milled" off very rapidly, thus requiring a premature reconditioning of the starter motor.

It is the essential object of the present invention to provide an improvement in or relating to starter drives whereby the above-mentioned inconveniences can be avoided by positively preventing the drive from reaching the engine toothed fly-wheel. This improvement is characterised primarily in that it comprises a device associated with the drive control means, which incorporates mechanical, electro-mechanical or other suitable means for positively retaining the drive in its inoperative position by locking or self-locking the whole or part of the drive.

the last fraction of its stroke, this core 4 moves the fork 11 to its inoperative position 11' shown in chain-dotted lines in FIGURE 1, the cross pin 9 being thus moved to position 9'.

When the starter is re-energized, the pin 9' of strap 10 firstly moves bodily with the core 4 along the lost-motion stroke "Cm" corresponding to the play J before abutting at 9" against the rear arm 15 of the U-shaped fork head so that this fork begins to rotate as shown in FIGURE 3. It is this lost-motion stroke which is utilized according to this invention for providing a simple yet efficient and economical solution to the problem of locking and releasing the starter drive.

According to a first form of embodiment of this invention, as shown in FIGURE 4, the strap 10 of core 4 of electromagnet 17 has formed therein elongated holes 18 having their major dimension directed at right angles to the core axis A-B; rotatably mounted in these elongated holes 18 is the pivot pin 19 of a roller 20 constituting the thrust member controlling the movements of fork 11 and therefore the starter drive 21; therefore, these holes 18 permit a slight vertical free motion of roller 20.

When the winding 22 of electromagnet 17 is de-energized and the drive resumes its inoperative position due to the action of the return spring 16 of the electromagnet, the roller 20 engages a bearing face 23 machined in the starter cover and parallel to the axis of translation A-B of core 4. The contour of the bottom 25 of the U-shaped fork head is so designed that it causes the roller 20 to be urged against said bearing face 23 when the fork 11 tends to pivot about its pivot pin 12 as a consequence of the effort exerted by the starter drive 21 which is transmitted through the pulley 26 to the shoes 13 of said fork 11. In this case, the drive 21 is locked against motion.

This locking action is released when the core 4 is attracted by the winding 22, as a consequence of the disengagement of roller 20 from said bearing face 23. In fact, when the roller 20 leaves the bearing face 23 it can move freely in a vertical plane due to the provision of the elongated holes 18. Thus, the fork 11 can pivot freely when the roller 20 has reached the front face 27 of the U-shaped fork head.

Conversely, when the energizing current has been cut out in the electromagnet coil and the magnetic field has thus been removed, the return movement is controlled by the return spring 16 after a cut-off stroke. Thus, roller 20 engages the rear face 28 of the U-shaped head of fork 11, and subsequently moves the drive 21 to its inoperative position. At the end of its stroke, the roller 20 is re-inserted between the bearing plane 23 of the starter cover 24 and the inner face 25 of the U-shaped fork head.

The arrangement illustrated in FIGURE 4 is of the locking type without any self-locking action, for in the inoperative position the bottom 25 of the fork head is substantially parallel to the plane of said bearing face 23 and thus the plays likely to exist or develop in the various mechanical connections are not taken up.

In a modified form of embodiment of this invention which is illustrated diagrammatically in FIGURE 5, the front bearing face 28' of the U-shaped head of fork 11 is inclined in the inoperative position, with respect to the axis of translation of core 4, so that if an effort "F" is exerted on the pulley 26 of drive 21, the force exerted by the return spring 16 against the core 4 and transmitted through the pin 9 of strap 10 creates a thrust applied to said fork 11 which tends to take up the plays of pulley 26 on drive 21, of shoes 13 on said pulley 26, and of fork 11 on its pivot pin 12. Under these conditions the fork 11 is locked by the engagement of strap 10 of core 4 against a roller 20 rigid with the cover 24 of the starter case, the inclination of the rear face 28' of said fork having an angular value so calculated that the reaction produced on the pivot pin 9 of strap 10 is sufficient to cause this strap 10 to be locked against said roller. The

frictional engagement thus produced between the thrust pin 9 of said strap 10 and the front face 28' of the fork head facilitates this locking action. The roller 20 also acts as a guide member to the core strap 10 when it is attracted by the electromagnet 17.

In a third form of embodiment illustrated in FIGURE 6 a frictionless self-locking action is obtained by providing in the strap 10 of core 4 an elongated hole 29 having its major axis directed vertically and adapted to receive freely therein the pivot pins 19 and 19' of a pair of superposed rollers 20 and 20' respectively. The bottom roller 20 engages with its lower portion the upper face 30 of fork 11 forming an acute angle α with the longitudinal axis of this fork, and provided with an upward projection 31. On the other hand this bottom roller 20 engages the top roller 20' of which the upper portion contacts an adjustment tapered portion 32 of a set screw 33 engaging a tapped hole formed in the end cover 34 of the starter motor, this screw being locked in the set position by a nut 34. A straight cam face may be substituted for the tapered portion of said screw.

Due to the action exerted by the return spring 16 the rollers 20 and 20' rolling on each other will ensure a firm, i.e. playless locking of the drive fork 11. Any movement of the drive mechanism 21 towards the flywheel ring will tend to pivot the lever-forming fork 11 in the clockwise direction and therefore to rotate the rollers 20 and 20' in opposite directions, whereby the top roller 20' will tend to move up the taper 32 and the bottom roller 20 will tend to move up the inclined plane 30 in order to reinforce the locking or wedging action. When the release is caused by the attraction of plunger core 4 by coil 22 the rollers 20, 20' will roll equally on the inclined plane 30 of fork 11 and on the adjustment taper 32.

According to a fourth form of embodiment illustrated in FIGURE 7 of the drawings the locking action is produced by means of a separate strap 35 shown in section. The core 4 is connected to this strap by means of a pin 36 movable in an elongated hole and adapted to slide in a tubular portion 37 of the strap. The front end of this tubular portion comprises notches 38 and the aforesaid pin 36 is adapted to engage the bottom of these notches when the core 4 is attracted by the coil 22.

Radial holes 39 formed in the tubular portion 37 are adapted to receive balls 40 which in the inoperative position of said core and fork 4, 11 engage a fixed cam face 41 formed in an inner annular groove or cavity 42. The core 4 is formed at its front end with a movable cam face 43 enabling the balls 40 to be disengaged from said fixed cam face 41 when the core is attracted. The strap 35 comprises at one end a cross pin 9 adapted to push the strap on the fork 11 and at the core end another cross pin 44 whereby the core 4 can push the strap 35.

When the drive 21 exerts an effort on the fork 11 by means of pulley 16 and shoes 13, and assuming that this fork 11 is in its inoperative position, the core 4, by holding the balls 40 in their outermost position, will lock the strap 35 and therefore the fork, since these balls engage the external groove or cavity 42 and are urged against the cam face 41 thereof.

According to a fifth form of embodiment shown in FIGURE 8, a bell-crank lever 45 fulcrumed at 46 interconnects the electromagnet core 4 and the fork 11. To this end, this fork comprises two slideways 47, 48 between which the push member 49 carried by the strap-shaped end of the outer arm of lever 45 is adapted to move. The other arm of lever 45 has formed therein another pair of slideways 50 and 51 receiving therebetween the push member or pin 9 of the strap-shaped portion 10 of core 4.

By properly calculating the angle β (of approximately 90°) formed by the slideway 47 of fork 11 and the straight line connecting the axis of the thrust pin 49 of said bell-crank lever 45 and its fulcrum 46, it is possible in the inoperative position of the fork to obtain a

knee-action locking this fork as a consequence of the efforts exerted by the drive 21 on the shoes 13 of said fork.

On the other hand, when the core 4 is attracted by the coil 22 the thrust pin 49 of bell-crank lever 45 causes the fork 11 to pivot about its fulcrum pin 12. Due to the specific kinematic arrangement resulting from the disposition of pins 9, 46 and 49, and also to the properly selected value of the angle of inclination of slideway 48, the pull produced by core 4 during the initial portion of its stroke can be multiplied or increased, this pull being on the other hand reduced during the last portion of this stroke, which is particularly advantageous considering the law governing the coercitive force of electromagnets.

A last exemplary form of embodiment of this invention is illustrated in FIGURE 9. In this modified structure the locking action is produced by using an auxiliary electromagnet having its coil 52 secured to an intermediate bearing 53 of the armature shaft 54 and adapted to hold the drive 21 in its inoperative position by exerting a magnetic pull thereon.

As shown in the wiring diagram of FIGURE 10, the winding 52 of this auxiliary electromagnet is not energized when the combination ignition and starting switch 55 is open (position O) or in the ignition and starting position shown in dash lines in the figure (position D), in which position the coils 2 and 3 of the control electromagnet are energized to attract the core 4 controlling in turn the main starter switch 5. The coil 52 is energized only when the aforesaid combination switch 55 is in its ignition position (position A).

To avoid a too fierce braking of the starter motor by the auxiliary electromagnet when the switch 55 is moved from its "start" position to its "ignition" position, and when the starter rotates at a relatively high speed, a rotary contact 56 for example of the centrifugal or friction type is inserted if desired in the circuit of coil 52.

Of course the present invention should not be construed as being limited by the specific forms of embodiment described hereinabove and illustrated in the attached drawings, since other modifications and variations may be brought thereto without departing from the spirit and scope of the invention as set forth in the appended claims.

What is claimed is:

1. A positive-control electric starter for an internal combustion engine, comprising: a shiftable drive device associated with a rotating shaft of the armature of an electric starter motor; pivotable shift lever means one end of which engages said drive device and the other end of which is fork-shaped; electromagnet means for controlling said drive device, said electromagnet means being energized through a starter switch; a core member forming a part of said electromagnet means and associated with the fork-shaped end of said shift lever means; resilient means for urging said core into its inoperative position; and locking means associated with said core and with the fork-shaped end of said shift lever means for positively restraining the shift lever means against rotation and thereby positively locking said drive device in its inoperative position when said core is in its inoperative position.

2. A positive-control electric starter according to claim 1, wherein the locking means is an electromagnet and is constituted by said electromagnet controlling said drive device, the core of said electromagnet being adapted to lock positively, by mechanical means, said drive device when said electromagnet is not energized.

3. A positive-control electric starter according to claim 1, wherein said locking means is an auxiliary electromagnet having a coil secured to an intermediate bearing of said motor armature shaft and adapted, when energized, to exert a magnetic pull on said shiftable drive device in order to hold it in its inoperative position.

4. A positive-control electric starter according to claim 2, wherein one end of said core member is strap-shaped and is provided with an elongated slot having its major axis disposed at right angles to the axis of said core member, and further comprising a roller carried on said strap-shaped end and having a pivot pin adapted to revolve in said elongated slot, the roller contacting, in the inoperative position of said starter, a U-shaped head of the fork-shaped end of said shift lever and further contacting a fixed flat face extending parallel to the axis of said core member.

5. A positive-control electric starter according to claim 2, wherein the end of said core member is strap-shaped, a thrust transmitting cross-pin is carried by said strap, the fork-shaped end of said shift lever is U-shaped and has an inner front face inclined in its inoperative position with respect to the axis of said core member, said front face constituting a bearing surface of said cross-pin when said shift lever is in inoperative position.

6. A positive-control electric starter according to claim 5, further comprising a roller having a fixed pivot pin, and wherein the upper face of said strap-shaped end of the core member is adapted to bear against said roller for guiding said strap face, during its translation and for locking said strap by the reaction of the fork-shaped end of said shift lever against said cross-pin.

7. A positive-control electric starter according to claim 2, wherein one end of said core member is strap-shaped, is provided with an elongated slot having its major axis directed vertically and adapted to receive freely therein the pivot pins of a pair of vertical tangentially superimposed rollers in rolling engagement with each other.

8. A positive-control electric starter according to claim 7, wherein the fork-shaped end of said shift lever has a face which forms an angle with the longitudinal center line of the shift lever and is engaged by the lower of said rollers in the inoperative position of said shift lever.

9. A positive-control electric starter according to claim 7, wherein an adjustment taper having an end screwed in the end cover of said starter motor is engaged by the upper of said rollers in the inoperative position of said shift lever.

10. A positive-control electric starter according to claim 7, wherein a straight cam face is rigid with the end cover of said starter motor and is engaged by the upper of said rollers in the inoperative position of said shift lever.

11. A positive-control electric starter according to claim 2, wherein said core member is adapted to slide in a tubular portion of a separate sliding strap inserted between said core member and the fork-shaped end of said shift lever, said strap being provided with a first cross-pin receiving the thrust of said core member, and a second cross-pin engaged in the fork-shaped end of said shift lever to transmit said thrust.

12. A positive-control electric starter according to claim 11, wherein said separate strap is provided in said tubular portion with recesses adapted to receive balls and with notches on the side nearest the shift lever.

13. A positive-control electric starter according to claim 12, wherein fixed cavities having a cam face are adapted to partly house said balls, said cam face constituting an abutment therefor.

14. A positive-control electric starter according to claim 12, wherein said core member is formed with a cam face and its end comprises a cross-pin, said balls being able to be released by said cam when said core member is attracted, and said cross-pin being adapted to engage the bottom of said notches of the separate strap.

15. A positive-control electric starter according to claim 2, wherein said core member has a strap-shaped head with a thrust pin moved between two slideways of

one arm of a bell-crank lever fulcrumed on a fixed pivot pin and interposed between said strap and said shift lever.

16. A positive-control electric starter according to claim 15, wherein said bell-crank lever has on its other arm a strap-shaped portion carrying a thrust pin and said shift lever has two slideways formed on its end, said pin being movable in said slideways causing said bell-crank lever to pivot about said fixed pin.

17. A positive-control electric starter according to claim 3, wherein said auxiliary electromagnet is fed through the combination of a starter and ignition switch of the engine only in the ignition position thereof.

18. A positive-control electric starter according to claim 17, wherein a centrifugal friction or like rotational switch is inserted in the energizing circuit of said auxiliary electromagnet in order to prevent same from becoming

energized in case the starter motor speed were abnormally high.
